UNITED STATES PATENT OFFICE.

MATT FÖLDY, OF SHARPLES, WEST VIRGINIA.

RAIL-LAYING TOOL.

1,200,333.

Specification of Letters Patent.

Patented Oct. 3, 1916.

Application filed January 25, 1916. Serial No. 74,166.

To all whom it may concern:

Be it known that I, MATT FÖLDY, a subject of the King of Hungary, residing at Sharbles, in the county of Logan and State 5 of West Virginia, have invented certain new and useful Improvements in Rail-Laying Tools, of which the following is a specification.

This invention relates to certain new and 10 useful improvements in rail-laying tools.

The primary object of the invention is the provision of a tool or implement serviceable both as a gage for spacing railroad rails in parallelism proper distances apart 15 and also providing a spike puller and a wrench for applying the fish plates in their operative positions.

A further object of the invention is the provision of a combination gage bar and 20 wrench handle having adjustable limit or spacing blocks shiftably mounted thereon with respect to a gage carried thereby.

In laying a railroad track, it is highly essential that the rails be secured to the 25 roadbed in parallelism, and the present tool is provided with a handle form of gage having adjustable blocks thereon for accurately spacing the rails apart the desirable distance, a removable wrench being attached at 30 one end of the handle for employment in securing the bolts to the fish plates for connecting the rails together, while a spike puller claw is integrally formed at the opposite end of the handle.

35 With these general objects in view and others that will appear as the nature of the invention is better understood, the same consists in the novel combination and arrangement of parts hereinafter more fully 40 described, illustrated in the accompanying drawings, and pointed out in the appended claims.

In the drawings forming a part of this application and in which like-designating 45 characters refer to corresponding parts throughout the several views:—

Figure 1 is a side elevation of the device. Fig. 2 is an edge elevation thereof, and Figs. 3, 4 and 5 are transverse sectional 50 views taken respectively upon lines III—III, IV—IV and V—V of Fig. 1.

The handle or gage bar 10 is substantially rectangular in cross section and is provided at one end with a curved extension 11 55 having a laterally beveled end 12 provided with a claw 13. The opposite end of the

bar 10 is provided with a recess 14 therein adapted for the removable reception of the shank or tang 15 of a wrench 16, a bolt 17 being provided for retaining the said wrench in position in substantial longitudinal alinement with the bar 10. The extension 11 being curved toward one edge 18 of the bar 10, the opposite edge thereof is enlarged or flared forming oppositely 65 projecting parallel flanges or guide ribs 19, the said flanges being substantially in the form of a right-angle triangle in cross section.

Spaced blocks 20 are slidably mounted 70 upon the guide flanges 19 by means of a longitudinal dove tailed form of side groove 21 with which each of the said blocks is provided. A set screw 22 is arranged upon each of the blocks 20 for engaging the adjacent edge 19 of the bar 10 for maintaining the blocks 20 properly spaced apart. Graduations 23 are arranged upon the opposite sides of the bar 10 and the adjacent outer faces of the flanges 19 and may be 80 after the form of the metric scale or the usual inch and foot graduations as herein illustrated and best shown in Fig. 1 of the drawings.

The base portions or feet 24 of the blocks 85 20 extend away from each other and toward the opposite ends of the bar 10, the said feet having flat end faces 25 adapted to engage the inner sides of adjacent rails for accurately spacing the rails apart. 90

In operation, the blocks 24 are adjusted upon the flanges 19, so as to position the block faces 25 at the required distance apart as denoted by the scale 23, it being understood that in laying the standard gage of 95 road, the rails are positioned four feet, eight and a half inches apart, and with the lower edge of the bar resting flatly upon the treads of the rails, the rails are drawn together until they engage the block faces 25 and are thus arranged in parallelism the requisite distance apart. 100

It will be noted that the flanges 19 provide the lower edge of the bar with greater area, whereby the bar may be readily seated 105 or positioned upon the rails, the blocks 20 further acting as weights for retaining the bar operatively arranged upon the treads thereof. The wrench 16 is employed for tightening the set nuts upon the bolts of 110 the fish plates for connecting the rails together in the usual manner, while the claw

13 may be utilized whenever desired for extracting the railway spikes and removing the fish plates and also the retaining bolts.

5 A serviceable tool is thus provided of special advantage in laying a railway track and providing a spacing gage, spike claw, and a fish plate wrench in a unitary structure.

10 While the form of the invention herein shown and described is what is believed to be the preferred embodiment thereof, it is nevertheless to be understood that minor changes may be made therein without departing from the spirit and scope of the invention as claimed.

15 What I claim as new is:—

1. A railway tool comprising a bar substantially rectangular in cross section and having longitudinal guide flanges at the

mounting edge thereof, the opposite sides of 20 the said bar and the adjacent outer faces of the said flanges being provided with graduations, blocks having dove-tailed grooves for the reception of said flanges, the said blocks being enlarged at their outer ends to provide rail engaging faces.

2. A track gage including a metal bar substantially rectangular in cross-section, the lower side edges of the bar being outwardly flared to provide guide flanges having graduation marks on the upper sides thereof, a pair of rail-engaging blocks having dove-tailed grooves therein slidably received on the flanged side of the bar, and means for holding the blocks in fixed relative positions. 30 35

In testimony whereof I affix my signature.

MATT FÖLDY.
